C. F. WRIGHT,
SAFETY DEVICE FOR PUNCHES,
APPLICATION FILED APR. 9, 1921.

1,433,329.

Patented Oct. 24, 1922.

Inventor
Charles F. Wright
by his Attorney
John O. Neam

UNITED STATES PATENT OFFICE.

CHARLES F. WRIGHT, OF AKRON, OHIO, ASSIGNOR TO THE DIAMOND MATCH COMPANY,
OF CHICAGO, ILLINOIS, A CORPORATION OF ILLINOIS.

SAFETY DEVICE FOR PUNCHES.

Application filed April 9, 1921. Serial No. 460,115.

To all whom it may concern:

Be it known that I, CHARLES F. WRIGHT, a citizen of the United States, and resident of Akron, in the county of Summit and State of Ohio, have invented certain new and useful Improvements in Safety Devices for Punches, of which the following is a specification.

This invention relates to a safety-device for punches and other moving machine elements; its object being to provide a guard of simple and reliable construction which can be bodily moved into and out of operative relation to said elements, and which guard has provision whereby access can be had to the interior of the structure when it is in operative position.

The invention has been more especially designed for use in connection with the book-positioning mechanism of machines for assembling match-books, such, for example, as illustrated in Letters Patent of the United States No. 1,217,991, dated March 6, 1917. Said mechanism comprises an oscillatory cylindrical head, or turret, having intersecting passages extending diametrically therethrough at right angles to each other, which passages receive match-books successively from an adjacent machine and position them beneath vertically - reciprocating punches operative to eject the books into an underlying receptacle. The present device is designed to encase the punch mechanism during the operation of the machine and thus serve as a protective guard for the fingers of the attendant.

The invention comprises a casing which is hingedly mounted adjacent the moving elements so as to be movable into and out of housing relation thereto, said casing including a door or doors that may be opened or closed when the casing is in housing position.

The invention also comprises features of construction which will be hereinafter described and claimed.

In the drawings—

Figure 1 is a side elevation of the guard-device as applied to the punch mechanism of a book-match assembling machine, only so much of the machine being shown as is necessary to illustrate the invention.

Fig. 2 is a plan of the structure shown in Fig. 1.

Fig. 3 is a perspective view of the guard-device detached.

Referring to the drawings, 5 designates the oscillatory book-positioning cylinder of a book-match assembling machine; 6 designates the vertical punches which reciprocate through the book-receiving chambers of said cylinder; 7 designates a connecting head for said punches, and 8 designates a power-actuated plunger for reciprocating the head and punches. 9 designates the receiving end of a receptacle into which the books are delivered from the cylinder, said receptacle being provided at its lower or receiving end with a bracket structure 10 in the spaced walls of which the cylinder is journaled.

The improved guard-device in its preferred form comprises an elongated casing constructed to provide a generally trianguloid enclosure for the punches, the head 7, and the upper portion of the plunger 8. This casing comprises a trough-like body 11 having a trianguloid cap-piece 12, and having also two curved doors 13 which are hinged, as at 14, to the respective longitudinal edges of the body 11 for swinging movement in opposite directions to each other in order to open or close the front and forward sides of the casing. Preferably the front of the doors, when closed, provide an open sight space 15 therebetween; but if desired the doors may be extended to close the front of the casing entirely. The lower rearward end of the body 11 is connected to the bracket 10 by means of a hinge 16, so that when the doors are swung open, as indicated by the dotted lines in Fig. 2, the casing can be bodily swung rearward in a manner to uncover the punch mechanism and thus facilitate its inspection, adjustment, repair or renewal, or for other purposes. (See Fig. 1.)

The upper ends of the doors are provided with upstanding lugs 17 which are resiliently coupled by a retracting spring 18 which assumes a position forward and rearward of the door hinges as the doors are closed and opened, respectively, as seen in Fig. 2, and thus tends not only to hold the doors in closing position when they are shut, but also to hold them in open position when they are opened.

When the guard-device is in its up-standing position and the doors are closed, the

punches and their adjacent connections are effectually encased, thus obviating accidental injury to the fingers of the attendant by the moving elements. If at any time a book or books should become jammed between the punches and the cylinder, either or both doors can be readily swung open in order to permit access to the mechanism.

My invention is not limited to the exact details of construction herein disclosed, as the same may be modified within the principle of the invention and the scope of the appended claims.

I claim—

- 15 1. In a safety-device for moving machine elements, a support adjacent said elements, a casing hingedly mounted on said support and movable into and out of housing relation to said elements, said casing including a door that may be opened or closed when the casing is in housing position.
- 20 2. In a safety-device for moving machine elements, a support adjacent said elements, a casing hingedly mounted on said support and movable into and out of housing relation to said elements, said casing including

two oppositely-disposed swinging doors that may be opened or closed when the casing is in housing position, and resilient means operative to maintain them in either open or closed position.

3. In a safety-device for moving machine elements, a casing comprising a trough-shaped body, a cap on said body, two doors hinged to the respective longitudinal edges of said body, and a spring resiliently connecting said doors and operative to maintain them in either open or closed position.

4. The combination with a match-book positioning element and reciprocating ejecting punches co-acting therewith, of a casing hingedly mounted adjacent said punches and movable into and out of housing relation thereto, said housing including a door that may be opened or closed when the casing is in housing position, and resilient means operative to maintain said door in either open or closed position.

Signed at Barberton in the county of Summit and State of Ohio this 7 day of April A. D. 1921.

CHARLES F. WRIGHT.
